1 Claim. (Cl. 274—2)

Automatic record-changing apparatus for talking machines are known which include a store of records and means for selecting and reproducing the records. In most apparatus the store is rectilinear or circular and forms an integral section of the support on which the apparatus is set. The records are housed in accordance with a predetermined classification in several compartments, so that they may be taken hold of by the jaws of an automatic arrangement. A number of said conventional apparatus include a carrier plate incorporating at both ends flanges rigid with the plate and interconnected by cross-bars which are interconnected in their turn by arcuate members the number of which defines the storing capacity of the records stored. Said apparatus show the drawback of requiring a manual reintroduction of the records into the store, this being performed in succession for the different records. In order to increase the number of available records, the producers equip their apparatus with stores containing as large a number of compartments as possible. However, the outer size of the apparatus increases simultaneously and it is necessary to resort to a middle course between a reduction in bulk and an increase in capacity of the store.

My invention has for its object an automatic record-changing apparatus which removes said drawbacks, said apparatus being of the type including a record store and an arrangement for selecting and reproducing the records. According to my invention, the store is constituted by a removable unit adapted to be readily changed and replaced, while means are provided for positioning the store in the apparatus in a manner such that the apparatus may be immediately ready for operation.

The accompanying drawing illustrates, by way of example, a preferred embodiment and a modification thereof

In said drawing:

FIG. 1 is an elevational partly sectional view of said embodiment.

FIG. 2 is a similar elevation view of a modification thereof.

The apparatus illustrated in FIG. 1 includes a supporting plate 1 carrying rails 2 over which a selecting and reading carriage 3 runs through the agency of its rollers 4. The carriage 3 is provided with a conventional mechanism which is not illustrated, which serves for locking, taking hold of and reading the successive records 5.

The free section of the plate 1 carries the flanges 6 which align the removable store between two upstanding edges. Said flanges 6 are parallel with cross-members 7 and 7' carrying parallel arcuate members 8, the successive

2

pairs of which define the compartments housing the records. The flanges 6 are provided with recesses 9 which allow removing the store through a raising movement with a view to substituting for it an identical store provided with a further series of records.

FIG. 2 illustrates a modification wherein the apparatus and its removable store are housed inside a portable case 10. On the inside of cover 11 is a downward projection 12. The cover 11 of said case engages tangentially at 12 the upper edges of the records so that said records 5 and the removable store carrying them are locked in position between three axial lines and are held fast during transportation. Said arrangement may be replaced by the use of a removable bar holding the parts in position, so that, upon mere closing of the cover or mere introduction of the bar, the apparatus becomes fit for actual transportation without any risk of shifting of the records or a release of the actual store.

My invention is not limited to the embodiments described hereinabove and it is applicable, generally speaking, to all types and shapes of record-carrying stores, whether rectilinear, curvilinear or circular, the object of the invention consisting in providing removable and interchangeable stores.

What I claim is:

Portable automatic record changing apparatus comprising means for selecting and playing records and record storing equipment contained within a housing having a lid in its upper part and abutment means in its base, said record storing equipment having abutment means in its lower portion and in its upper portion, spaced compartments in each of which a record can be held so that it projects substantially above the level of the store, said abutment means of said store being removably engaged with that of said housing so as to locate said record storing equipment in said housing, said lid having a downward projection on the inside thereof, closing of said lid causing said projection to be urged into downward pressing engagement with records in position in said record storing equipment.
